UNITED STATES PATENT OFFICE.

DANIEL B. McTAGGART, OF BUTTE, MONTANA.

AUTOMATIC TRAIN-PIPE CONNECTOR.

1,331,939.

Specification of Letters Patent. Patented Feb. 24, 1920.

Application filed March 18, 1918. Serial No. 223,223.

To all whom it may concern:

Be it known that I, DANIEL B. McTAGGART, a citizen of the United States, residing at Butte, in the county of Silverbow and 5 State of Montana, have invented a new and useful Automatic Train-Pipe Connector, of which the following is a specification.

The present invention relates to improvements in automatic train pipe connectors, 10 the primary object of the invention being the provision of a connector for train pipe, air signal, hose, and electrical connections upon passenger and freight trains, and train or air brake pipe, air signal and all hose, 15 pipe or electrical wiring connections upon freight trains, the present invention being readily applied to cars now in use, without the discarding of the present equipments, and also being so constructed as to permit 20 cars not equipped with the present connector to be connected thereto.

The invention contemplates improvements in that form of train-pipe connector set forth in Letters Patent numbered 1,094,670, 25 issued April 28, 1914.

A still further object of the present invention is the provision of a train pipe connector, which is supported by the knuckle joint of a car coupler by means immediately 30 below and in vertical alinement with the knuckle pin.

Another object of the invention is the provision of means for locking the connectors in position when uncoupled.

35 A still further object of the present invention is the provision of a train pipe connector carried by the car-coupler and so mounted as to be brought into registration when non-alining car-couplers, due to the 40 varying load conditions of the cars, are brought together, the train pipe ports of the connectors being brought primarily together before the car-couplers engage, the final engagement of the car-couplers moving the 45 connector members from an inclined position to a right-angle and in locked position to insure the non-leakage of the connector ports, and the closure of the main valves.

A still further object within the contemplation of the invention is the production 50 of a simple, durable and efficient connector.

With the foregoing and other objects in view, which will appear as the description proceeds, the invention resides in the combination and arrangement of parts and in 55 the details of construction hereinafter de-

scribed and claimed, it being understood that changes in the precise embodiment of the invention herein disclosed can be made within the scope of what is claimed without departing from the spirit of the invention. 60

Practical embodiments of the invention are shown in the accompanying drawings, wherein:

Figure 1 is a view in side elevation of two 65 abutting car-couplers with the present connector members in their initial connecting position;

Fig. 2 is a horizontal section through the connector showing the same in coupled position; 70

Fig. 3 is a fragmentary detail view in elevation of the knuckle pin;

Fig. 4 is a view in side elevation, partly in section, of a modified form of connector 75 mounting;

Fig. 5 is a fragmentary detail sectional view taken on the line 5-5 of Fig. 4.

Referring to the drawings by characters 80

The letters A and B designate the two car-couplers, which are of usual construction and are each provided with a knuckle-pin 1, the respective mating train pipe connector members C and D, being carried thereby and for limited swinging horizontal movement and rectilinear vertical movement, as will presently appear. As 85 each connector member is identical with the other the description of one will suffice for both and, in order to describe the simplest embodiment, a freight train equipment will be described in which only the air-brake connection is carried. 90

Each connector member comprises the 95 casing 2 having the knuckle-pin fitting aperture 2', and provided with a socket 3, at the end of which is the centrally located, inwardly projecting annular flange 4 forming a centering and holding element for one 100 end of a compression spring 5, the other end of which fits within a socket 6 formed at the rear end of a slidable shank 7. This shank 7 is provided with an elongated slot 8 which 105 extends longitudinally thereof, and which fits about the pin 1, and thus permits the necessary sliding movement of the shank 7. The shank 7 carries, or has formed integral therewith, a connecting head composed of the lug 9 of relatively great width and having the inclined outer face 10 and with the 110 guide arm or finger 11 in spaced relation to

the lug 9, the cross wall 12 between the lug 9 and the finger 11 being inclined to accommodate the inclined outer face 10 of the lug 9 of a mating member. Beyond the outer 5 face of the guide arm or finger 11 is a lug or arm 13, provided with a port 14 whereby a coupler (not shown) may be coupled in the usual manner with the ordinary hose pipe carried by the car, so that air will be di- 10 rected through the port 15 and through the port 16, formed in the inner face of the lug 9, and in coactive relation to a similar port of the mating connector.

In the outer face of the lug 9, and in 15 transverse alignment with the port 16, is a counter-bore 17 in which is slidable a plunger 18, the plunger carrying a cup washer 19 for the purpose of preventing the escape of air about the plunger. A stem formed 20 with a spider 20 is bound to the plunger by means of a screw bolt 21, or otherwise, and the spider reciprocates within a counter-bore 22 for the purpose of limiting the movement of the plunger. When the connector members are in coupled or connected 25 position, the plungers 18 are forced inwardly by the faces 11' of the fingers 11, and the pressure of air against the inner faces of these plungers tends to force the 30 inner faces of the lugs 9 toward each other and bring the port rings or gaskets *a* into intimate contact.

A valve 24 is carried by the arm 13 for the 35 purpose of closing the channel 15, the same being provided with a port 25, and with the two venting ports 26 and 27, the venting ports being disposed to register with ports 28 and 29, respectively, formed in the arm 13 and communicating with the 40 atmosphere, when the valve 24 is turned to close the channel 15. The valve 24 is provided with a stem (not shown) to which is attached a bell crank lever 30 and which is actuated to rotate the valve as set forth in 45 Patent Number 1,094,670, heretofore mentioned, or in other suitable manner. A pull chain 31 may be provided on the lever 30 so that a brakeman or other attendant may actuate the valve when desired for any purpose. In order to properly support each 50 connector member, and also to provide a means which will insure the proper registration of the mated members, should the car-couplers be out of horizontal alignment, due to variously loaded and empty cars, a spring 32 is disposed upon the lower end of the pin 1, and holds the member 2 upwardly toward the underside of the car-coupler, and carried by the car-coupler is the spring plate 33, whose curved end 34 is disposed to be 55 engaged by the under face of the end 35 of a mating car-coupler to be depressed to engage the upper face of the member 2, and thus move the connector member carried by 60 the same car-coupler as the spring 33 to be 65

moved downwardly and into alignment with the mating connector member. The connector members are thus brought into position with their ports accurately registering. The end of the car-coupler is usually beveled 70 or sloped off to save metal and reduce weight so that, when the present connector is attached to the ordinary equipment, it becomes necessary to weld a lug or strip on this end to bring it level and in position to 75 contact the spring plate 33. When the equipment is being designed especially with a view to the use of the present connector, the car-coupler may be cast in the proper shape to provide the end 35. 80

To provide means for locking or holding the connector elements or members in position when uncoupled, and at the same time allow vertical movement to such members, which is one of the main features of the 85 present improvement, a groove 36 is formed longitudinally of the pin 1, which groove is adapted to receive a rib 37 which projects into the slot 8 of the shank 7 from the wall at the rear of said slot. As the connector 90 member rocks horizontally upon the pin 1 as it separates from its mating member when the car-couplers are uncoupled, the rib 37 enters the groove 36, being in position to do so by reason of knuckle pin 1 95 having been turned through an angle of 120 degrees to bring the groove 36 into registry with the rib 37, the rib is then forced against the face of the pin 1 under the action of the compression spring 5 as 100 the mating members separated. In order that the knuckle pin may be retained in proper position, a lug 38 is provided thereon and is adapted to enter a recess, not shown, which is formed in the coupler head. 105

In the modified form shown in Fig. 4 a depending tubular hanger or support is cast integral with the coupler head A' or is welded thereon, and this hanger is positioned immediately below and in vertical 110 alignment with the knuckle pin 1'. The tubular member or hanger 39 has a groove 36' formed longitudinally thereof to receive the rib 37 of the shank 7 when the connectors are in separated position. A 115 compression spring 32' surrounds the lower end of the tubular hanger 39 and serves to force the casing 2 upwardly against the spring plate 33 and coupler head A'. The spring 32' is held in place upon the hanger 120 39 by a collar 40 which is bound upon the hanger by a bolt 41 or otherwise.

During the uncoupling operation, the appliance rotates around a fixed knuckle pin, through an angle of about 45 degrees, or to 125 a position where the lugs 37, which are pressed forward by the springs 5 engage within the slots 36, as indicated by Fig. 5 of the drawings:

In the coupling operation, the forward 130

portions of the appliances engage with each other, and the forcing together of the cars, and the engagement of the couples, causes the appliance to then rotate around the 5 knuckle pin, forcing lug 37 out of slot 36, leaving the lug 37, in a position as indicated by Fig. 2 of the drawings.

Having thus described the invention, what is claimed as new and sought by Letters 10 Patent, is:—

1. A train pipe connector for attachment to the knuckle-pin of a car-coupler, including a carrying member, a spring projected head having connecting portions and a channel therethrough having bleeding vents leading therefrom to the atmosphere, a valve for controlling the passage of fluid through the channel and having a port to each bleeding vent and for registration therewith 15 20 25 30
- when the valve is in closed position, and means carried by the spring projected head and engaging the knuckle-pin when the head is projected for locking the carrying member against rotation on the knuckle-pin.
2. The combination with a car-coupler, of a train pipe connector mounted beneath the coupler, said connector including a casing mounted for vertical sliding movement and horizontal swinging movement about an axis coincident with a prolongation of the axis 35 of the knuckle pin, a knuckle pin having a

groove therein, and a connector head carried by the casing and formed with a rib to engage said groove of the knuckle pin.

3. The combination with a car-coupler, of 35 a train pipe connector mounted beneath the coupler, said connector including a casing, a spring projected shank slideable in the casing, a connector head carried by the 40 shank, means limiting the projection of the shank, and means carried by the shank and engaging the limiting means when the shank is projected for locking the casing against horizontal swinging movement.

4. In combination with a car-coupler, a 45 train pipe connector including a casing, a spring pressed slideable shank in the casing, said shank carrying a rib, a knuckle pin movable in the shank, said knuckle pin having a groove therein, said rib adapted to engage within the groove of the knuckle pin when the connector is in one position for locking the connector elements in position when the coupler is uncoupled.

In testimony that I claim the foregoing 55 as my own, I have hereto affixed my signature in the presence of two witnesses.

DANIEL B. McTAGGART.
